UNITED STATES PATENT OFFICE.

FRANCIS D. HOLBROOK, OF CHICAGO, ILLINOIS.

CLAW-BAR.

SPECIFICATION forming part of Letters Patent No. 746,083, dated December 8, 1903.

Application filed November 21, 1902. Serial No. 132,292. (No model.)

To all whom it may concern:

Be it known that I, FRANCIS D. HOLBROOK, a citizen of the United States, residing at Chicago, in the county of Cook and State of Illinois, have invented certain new and useful Improvements in Claw-Bars, of which the following is a specification.

My invention relates to claw-bars, and especially to devices of this kind adapted for extracting rail-spikes from ties.

The main object of my invention is to provide a novel device of this class which extracts spikes without bending them.

Another object of my invention is to provide a claw-bar in which the jaw is movable on the handle in order to increase or decrease the angle between the parts to adjust the jaw on the handle, so that it may be struck on the spike when the angle is decreased, and then employed to draw the spike in a practically straight line when the angle is increased.

Other objects of the invention will be apparent from the description and appended claims.

With these objects in view my invention consists in the organization and arrangement of the several parts, as hereinafter described and then pointed out in the appended claims.

In the accompanying drawings, which illustrate my invention, Figure 1 is a perspective view of a section of a rail, showing my claw-bar in position in extracting a spike. Fig. 2 is a part sectional and part side view of the parts shown in Fig. 1 and shows the claw-bar in its two extreme positions by dotted and full lines. Fig. 3 is a detail view showing the jaw in central section and the lower portion of the handle in side elevation; and Fig. 4 is a view similar to Fig. 3, but showing the claw-bar in operative position to a rail and spike and illustrating two intermediate positions assumed by the parts between the extreme positions of Fig. 2.

Referring to the drawings, the letter A indicates a handle of suitable length, in practice about five feet, and provided with an angular foot A', having a rounded base or curved lower edge a and a rear heel a'. The front face a² of the foot is substantially vertical when the foot rests upon its base, and

is provided with an upwardly-facing shoulder a³.

The jaw B is provided with the usual claw b and is curved in any suitable manner, having a rounded base b'. In the rear portion of the jaw a slot or mortise b² is cut, into which the shouldered end of the handle fits, the parts being detachably secured by means of a suitable bolt C or any other means allowing the convenient detachment of these parts. The mortise is preferably slightly flared upwardly, and the foot of the handle is correspondingly thickened at its base, whereby a more extended bearing-surface is provided 65 to rest upon the ties. The inner face or wall b³ of the mortise is provided with a downwardly-facing shoulder b⁴, which is adapted to coact with the shoulder a³ of the handle.

When the device is used, the parts may be first placed in the relation shown in full lines in Fig. 2 and in Fig. 3, wherein the angle between the handle and jaw is decreased, and with the faces a² and b³ in engagement, in which position the claw may be struck upon the spike when necessary after the fashion of striking down with a mattock, and the claw thereby forced upon the spike. Where the spike is not sunk too deep into the tie, the claws may be worked under it, or the operator may strike his foot against the heel a' of the part A' to force the claw upon the spike, the conformation of the coacting faces of the parts A' and B serving to direct the force so employed in the line of the claw. When the 85 claw is brought into engagement with the spike, as shown in full lines in Fig. 2, the handle is then drawn back away from the spike and rail, the shoulders a³ and b⁴ thereby being brought into engagement, and the 90 parts will assume the position shown by dotted lines in Fig. 4, the curve of the base b' of the jaw forming a preliminary or initial fulcrum and allowing the parts to move forward, so that the spike is entirely within the claw. 95 Continued pressure on the handle causes the parts fulcrumed on the curve of the base b' and the lower edge of the foot A' to successively assume the positions indicated in dotted and full lines in Fig. 4 and then in dotted lines in Fig. 2, the curved formation of the parts allowing the jaw to slide forward 100

By means of the curves of the jaw and foot the jaw is forced forward toward the rail during the progressive upward movement of the spike, and thereby maintains its claw ⁵ *b* in practical alinement with the spike, whereby the latter is extracted without bending, the final fulcrum being on the heel *a'*. The jaw being movable on the handle is readily adjusted to its different positions and being detachably connected with the handle may be easily removed when worn or broken for replacement.

While the coacting faces *a²* and *b³* of the handle and jaw, respectively, will operate satisfactorily if plain, I prefer to employ the shoulders, as they provide a more positive engagement of these parts and take the strain off the connecting-bolt.

Having described my invention, what I claim as new, and desire to secure by Letters Patent, is—

1. A claw-bar consisting of a handle hav-

ing an angular foot the front face and base of which are at substantially right angles, a claw pivoted on the end of the bar and having a shoulder coacting with the front face of the foot and a curved base forming a preliminary or initial fulcrum in front of the bar, and the foot having a rear heel forming the final fulcrum.

2. A claw-bar consisting of a bar or handle having a foot, and a jaw pivoted on the handle and having claws, the base of the jaw forming a preliminary fulcrum, the foot having a curved base to form a changing fulcrum and also having a rearwardly-projecting heel to form the rear and final fulcrum.

In testimony whereof I affix my signature in presence of two witnesses.

FRANCIS D. HOLBROOK.
